UNITED STATES PATENT OFFICE.

HERMANN F. CUNTZ, OF HARTFORD, CONNECTICUT, ASSIGNOR TO AMERICAN RADIUM COMPANY, OF NEW YORK, N. Y., A CORPORATION OF NEW YORK.

HAND AND INDICATOR FOR WATCHES AND LIKE ARTICLES.

1,415,158.

Specification of Letters Patent.

Patented May 9, 1922.

Original application filed July 2, 1921, Serial No. 482,095. Divided and this application filed October 12, 1921. Serial No. 507,240.

To all whom it may concern:

Be it known that I, HERMANN F. CUNTZ, a citizen of the United States, resident of the city of Hartford, county of Hartford, 5 and State of Connecticut, and whose post-office address is No. 7 East 42nd Street, borough of Manhattan, city, county, and State of New York, have invented certain new and useful Improvements in Hands and Indicators for Watches and like Articles, of 10 which the following is a specification, reference being had to the accompanying drawings, illustrative of particular embodiments of my invention, this being a division of my 15 application Serial No. 482,095, filed July 2, 1921, allowed October 3, 1921.

This invention relates to indicators such as the hands of clocks, watches, gauges, meters and other devices, and instruments, and 20 for like or similar devices, as may appear from the following specification. Particularly in such indicators the invention relates to providing them in a form or construction permitting advantageous equipment with luminous material, so that the indicators or hands may be readily visible and readable at night and at the same time affording accurate and easy reading or readily discerning of an indicator or indicators 25 and their position with respect to graduations by outside light such as by daylight or when visible by ordinary illumination.

The application of luminous material involving compounds of radio-active and 35 radio-responsive material, has heretofore been practised by embodying such permanently luminous compounds in a recess in the hands of instruments and particularly in watch and clock hands so that a sufficient bulk of 40 the material is held spread over a sufficient area to provide an amount of luminosity to an extent and for a sufficient distance suitable for the particular instruments or case involved; or in some cases the permanently 45 self-luminous compound is spread over the surface of a hand with suitable protective covering to keep it in place. A reasonable area is required with a considerable width with respect to the length in a line, intended 50 to be luminous in the dark, sufficient to provide visible luminosity at a distance of a foot or several feet or yards,—depending

upon the particular use to which the permanently illuminated article is adapted. In view of the relatively larger width of line 55 required for this darktime luminous effect, the indicator, hand or pointer are of a greater width than permits accurate reading, in the daytime or under conditions of ordinary outside illumination. It, therefore, 60 becomes a problem to provide such devices with permanently luminous material in a manner whereby accurate reading of the time or accurate reading of instruments, as to the registration of pointers with graduations, can be assured or in any event can 65 become a matter of greater accuracy than has heretofore been the case by day and night.

In the case of pointers or indicators and 70 hands for watches, a broad surface covered with radio-luminous material, backed up by a relatively dark background involves all the inaccuracy incident to a broad line compared with a very fine hair line or narrow 75 marker which should be used in ordinary or full illumination for accurate determination of calibration registration. I, therefore, provide a pointer or hand with surface of a 80 relatively sufficient width to carry an ample area of radio-luminous material for the desired degree of visibility in the darkness, but I provide medially or in the axis of such a pointer or hand, a narrow contrasting line of non-luminous material and of 85 contrasting color with the luminous material in the daytime or when subject to outside illumination. Such central line of non-luminous material provides for accurate reading in the daytime and the provision of 90 such a line whether on the pointer, calibration, marking or numerals, supplements the art heretofore known by giving to the use of radio-luminous compound on instruments and other devices an assurance of accuracy 95 for ordinary reading by outside light which has not heretofore been the case.

The provision of such distinct non-luminous accurate marks, whether in an indicator or in a graduation, or otherwise, involves 100 modifications from structures heretofore used, which may be provided in numerous ways but require structural changes in such parts not heretofore known and of

which particular embodiments I have here-with illustrated and will now describe in more detail with reference to the accompanying drawings, in which:

5 Fig. 1 is a plan view of a pointer or hand with the daytime reading line in arrow-head at the tip and centrally throughout the main body of the pointer.

10 Fig. 2 is a cross-section of a pointer on the line 2-2 of Fig. 1.

Fig. 2^a is a similar cross-section of a pointer showing a modified form of attachment for the medial daytime reading line.

15 Fig. 2^b is a cross-section of a pointer with a modified form of arrangement and connection between the base and the daytime reading line.

20 Fig. 3 is a plan view of the pointer in Fig. 2, showing the contrasting daytime reading lines compared with the radio luminous field.

Fig. 4 is a side elevation of Fig. 1.

25 The pointer or hand A comprises a strip of very thin material and which is usually metal and preferably steel, which is formed with the usual hub a and terminates at the opposite end with its side converging to a point a'. As shown, the middle of the strip is crimped to form a ridge B, and the converging edges near the tip are turned up to form lateral converging ridges C. These ridges B and C, and particularly the former, give a horizontal stiffness so that the strip of which the hand or pointer is made may be 30 of thinner material than usual, with the ridge B forming a strengthening medial flange or web. However, the height of this central rib is such as to provide between it and the border or sides of the strip a recess which provides for the embedding of a layer of radio-luminous material on either side of the central rib and extending to the edge or as near 35 the edge of the strip as desired.

40 The central rib permits the embedding of the radio-luminous material D in a manner that affords sufficient contact of the material and a vehicle or coating which holds the radio-luminous material to the pointer,—but also permits uniform and ready application on either side of the middle ridge, whereby the ridge is left clear and clean of 45 luminous material and being of a contrasting color, such as blued or otherwise treated steel, it constitutes a uniform dark medial line as 50 viewed in the daytime compared with the lateral areas of light colored radio-luminous compounds. The radio-luminous compound area can extend directly to the point within the converging ridges C-C whereby a 55 pointed luminous area affords the desired visibility in the dark, while the ridges C-C protect the tip and keep the radio-luminous material more permanently in position for a long period of years, resisting the jarring 60 or vibration or other effects incident to the 65

usual usage of the pointer or hand. By providing the area in arrow-head shape, as shown without the central parting for a short distance from the tip, the most important portion for night reading, namely, 70 the end of the radio-luminous hand, is also better protected to resist dislodging of the radio-luminous material due to any variation in temperature or in contracting of the material. Throughout the remaining length of 75 the hand, the lateral radio-luminous material areas may be divided into sections so as to better resist loosening due to contraction of the radio-luminous material and the vehicle used to secure it to the surface and to the 80 lateral walls of the ridge, or the lateral edges may be in part or continuously turned up as in Fig. 2^a, and otherwise modified.

Terminating the ridge B part way between the tip and the hub a makes it possible to 85 efficiently and uniformly apply the radio-luminous material on the outer portion of the hand or pointer, for the desired length of self-luminous area, and to omit it from the portion near the hub in order to save the expense of radio-active material.

90 In cross-section the hand may be readily made with the crimp B, as shown in Fig. 2, with respect to convenience of manufacture of the hand proper, and after depositing the material for the self-luminosity the artisan can readily manipulate a tool across the ridge B in order to clear the surface of the ridge, leaving its contrasting color surface clear, and thereby assuring uniform thickness or 100 depth of material for luminizing in the dark on such length of the hand as desired.

95 The construction shown in Fig. 2^a involves the base J of the hand or pointer with a central slot into which a bent strip K is forced with oppositely extending lips or flanges, which has at its outer edge the narrow surface H which may be bent or formed as rounded or flattened to provide the necessary breadth or width of the line which is 105 to form the daylight reading mark of the hand. In this form the walls of the ridge member K may be so formed as to be reentrant to give an added value in the holding of the laterally disposed radio-luminous 110 material, and if desired the edges may in part or whole be slightly turned up as shown.

115 In Fig. 2^b the modification in the cross-section involves the base L on one side of which a small wire M is laid and secured thereby forming a ridge to provide the medial day-reading line and to laterally provide for holding the radio-luminous material.

120 It will thus be seen that the constructions described provide a ridge or ridges intermediate the side edges of a hand or pointer, which aid to secure, and which can serve to assure uniform thickness of the radio-luminous material applied to the surface of the 125 130

base. Furthermore, the ridge of rigid material forms the upper limit of the hand structure with the base at the bottom, so that both top and bottom are protected during the operation of the hands or pointers against interfering objects which might otherwise dislodge the radio-luminous material in the absence of the protecting ridge. The structure also serves to accommodate most advantageously the application of radio-luminous material in different ways, as, for example, the principal ingredients, namely, the radio-responsive material may be very quickly applied to hands of my construction, because the ridge in its various arrangements serves to control the thickness and assure the efficiency of the application of material either in base or other form with entire uniformity throughout the length of the head which it is desired to cover; thereafter the radio-active material of far lesser relative quantity may be readily dusted onto the surface or sprinkled on to the radio-responsive or sub-compound, as it is sometimes called. And in any finishing operations the manipulation of the tools will be subject to the control of the ridge in conjunction with the material borders of the hands, whereby uniformity of finish with economy in the operation is a result of great advantage from a manufacturing or studio work standpoint.

It will also be realized that a narrow line provided in the structure of hands or dials as heretofore described, as well as many modifications thereof, supplies a daytime visibility of a fine hair line which may be so narrow that it will in no way interfere with the luminosity in darkness of the adjacent radio-luminous areas. The light emission from radio-luminous areas is such that with a total area, and with a width of luminous line in proportion to its length, sufficient for the desired legibility in the dark for a watch or clock or any other particular use, means that such light emission will have substantially the value of the entire area of the hand or figure, and for night observation the narrow uncoated central ridge will not appear, i. e., it will practically be bridged by the light emission from the adjacent luminous areas.

Conversely, hands or figures constructed and formed as heretofore described may be of white or light tints matching the adjacent enamel color of a dial underlying the hand, in which cases watches or clocks with their reading parts so constructed will have in daytime a substantially invisible breadth of hand, but a narrow clearly visible line, even a hair line, will constitute the central indicating or reading marking for the hand and for the dial marking or figure with just as great accuracy for daylight use as any ordinary watch, clock or other indicating device,—and with no apparent increased

breadth in the markings or hands during daytime reading.

The revolutionary development involved in the introduction of readable-in-the-dark watches, clocks, compasses and other indicating instruments and devices, is well known to have involved at first the serious objection of making very broad hands and either large dots or graduations or broad figures in order to provide a sufficient area so that the permanent self-luminosity or radio-luminous materials would serve the night reading object. The clumsiness of such structures impeded for years the more general adoption of the day and night reading-parts of timepieces and other instruments, and the necessity for providing means so that the same night visible instruments would be equally readable by day, led to the provision of a border, or more properly two borders, one on either side of the self-luminous area. Such borders on broad hands were an initial objection criticised as "clumsiness", which the general usefulness of the self-luminous markings has but partially overcome. Initial attempts in the case of some instruments led to the use of a contrasting background, so that the white hand was bordered by a dark background but this only made day reading relatively visible but still involved the broad and inaccurate mark

which is white for day reading and has the same objections for many classes of timepieces as well as other devices. Added to the solution of the problem of producing reading parts of time pieces or other devices which can be accurately read in the daytime, it will be seen that the structures heretofore described have many added advantages, such as assuring uniformity in the amount or depth of the coating of radio-luminous material, and stiffening the pointers and permitting the use of the thinnest obtainable sheet material for the base of hands or pointers, in order to reduce the total thickness of the hands as well as to provide uniformity throughout the length of area of the luminous surfaces. Other advantages will be appreciated in the practice of this invention, facilities for manufacture, as well as economies and speed of production with uniformity of product, add to the value and durability and other characteristics of the finished product.

While various modifications may be made in the structure and arrangements, as well as the material and use of the articles, of which specific embodiments have been heretofore described, I do not confine my invention to the specific forms shown in the accompanying drawings and herein specified in detail, but what I claim and desire to secure by Letters Patent is:

1. An article of the character described comprising a thin flat base, two converging

ridges near the outer end and a single central medial ridge formed on the base from near the tip toward the hub.

2. A hand or pointer for watches and like articles for dark and light reading, including a base, a narrow medial non-luminous mark and a relatively broad radio luminous area on either side of said non-luminous mark substantially the width of the 10 base, and converging non-luminous borders of contrasting color near the outer end.

3. A hand or indicator for watches or like articles comprising a broad base, radio luminous material covering the top side of 15 the major portion of the base, a medial non-luminous line extending radially from the hub centre of the hand and lateral juxtaposed ridges on opposite sides of the hand

extending a minor length of the hand, for the purpose described.

4. A hand for watches for night and day reading, comprising a base, a relatively narrow medial ridge, a border of radio luminous compound on either side of said ridge superposed on said base, a lateral protecting ridge for said luminous compound in proximity to the tip of the hand.

In testimony whereof, I have signed my name to this specification, in the presence of two subscribing witnesses, this 10th day of October, 1921.

HERMANN F. CUNTZ.
